United States Patent Office.

MARTIN H. CRANE, OF CINCINNATI, OHIO, ASSIGNOR TO CRANE, BREED & COMPANY, OF SAME PLACE.

Design No. 2,552, dated January 15, 1867.

DESIGN FOR A BURIAL-CASE.

The Schedule referred to in these Letters Patent and making part of the same.

TO ALL WHOM IT MAY CONCERN:

Be it known that I, MARTIN H. CRANE, of Cincinnati, in the county of Hamilton, and State of Ohio, have invented a new Design for a Burial-Case; and I do hereby declare that the same is represented in the accompanying drawing, which is made part of this specification.

I claim as new, and desire to secure by Letters Patent, the design for a burial-case, represented in the accompanying drawing.

In testimony of which invention I hereunto set my hand.

M. H. CRANE.
